J. M. SMITH,
COMBINATION INK BOTTLE AND INKWELL,
APPLICATION FILED AUG. 13, 1919.

1,322,144.

Patented Nov. 18, 1919.

UNITED STATES PATENT OFFICE.

JOHN M. SMITH, OF NEW YORK, N. Y.

COMBINATION INK-BOTTLE AND INKWELL.

1,322,144.

Specification of Letters Patent. Patented Nov. 18, 1919.

Application filed August 13, 1919. Serial No. 317,212.

To all whom it may concern:

Be it known that I, JOHN M. SMITH, a citizen of the United States, residing at New York city, in the county of New York and State of New York, have invented certain new and useful Improvements in Combination Ink-Bottles and Inkwells, of which the following is a specification, reference being had to the accompanying drawings.

10 This invention relates to an improved combination ink bottle and ink well, and an object of the invention is the provision of a device of this kind designed to prevent supplying too much ink to the pen. In other words, the bottle includes an ink well which may be filled and raised to the top of the bottle, so that the pen may be supplied with the requisite amount of ink, thereby preventing the pen from being dipped 15 too far into the ink which would soil the holder as well as the fingers in time.

By the provision of a device of this kind, the entire contents of the bottle are prevented from being lost when the bottle is upset.

25 A further object of the invention is the provision of a device of this kind comprising a bottle having an ink well mounted therein and adjustable whereby the ink well may be raised and connected within the neck 30 of the bottle. Hence, should the bottle be upset, but a small portion of the ink will be lost.

A further object of the invention is the provision of means for emptying and refilling the ink well, while the bottle is in a vertical position.

40 A further object of the invention is the provision of a combination ink bottle and ink well comprising novel features of construction. One of the features of construction consists in the provision of a tubular connector between the cork proper of the bottle and the ink well, in which a valve stem is mounted provided with a valve at its 45 lower end and which valve is provided with an opening to coöperate with an opening in the ink well, whereby the well may be emptied or filled.

50 Another feature of the invention is the provision of means for rotating the valve stem and holding the valve stem in different adjusted positions.

While the design and construction at present illustrated and set forth is deemed preferable, it is obvious that it is susceptible to

changes, when reducing the device to a practical form for commercial purposes, and the right to these changes is claimed, provided they fall within the scope of what is claimed.

60 The invention comprises further features and combination of parts as hereinafter set forth, shown in the drawings and claimed.

In the drawings:

Figure 1 is a perspective view of the combination ink bottle and ink well constructed in accordance with the invention;

Fig. 2 is a vertical sectional view through the same, showing the ink well in its lower-most position in the bottle and disclosing the 70 valve in its open position; and

Fig. 3 is a vertical sectional view showing the ink well raised and threaded into the neck of the bottle, whereby the ink in the well may be used, the valve being closed to prevent the return of the ink to the bottle.

Referring to the drawings, 1 designates an ink bottle which may be of any suitable proportions or configurations, provided with a neck 2, the inner wall of which has threads 3. A cork 4 is mounted in the neck and has secured thereto a wooden top piece 5. A tubular extension 6 extends through the cork and downwardly into the ink bottle. The upper end of the tubular guide has an annular disk 7 which is secured between the cork and the wooden top piece 5. The lower end of the tubular guide has a disk 8 and rotatably mounted in the extension is a valve stem 9. A valve 10 is carried at the lower end of the stem 9 and is provided with an opening 11.

An ink well 12, which may be constructed of any suitable material, preferably metal or the like, is arranged in the ink bottle and its bottom 13 has a central opening 14, through which the stem 9 passes. In this way the bottom of the ink well is interposed between the disks 8 and 10. The bottom 13 of the ink well has an eccentrically arranged opening 15 with which the opening 11 is adapted to coöperate for emptying or filling the ink well.

105 A disk 16 is mounted upon the upper end of the valve stem 9, there being a screw 17 passing into the end of the stem 9 to hold the disk 16 to the stem. A suitable washer 18 is interposed between the disk 16 and the wooden top piece 5 of the cork. Extending downwardly from the disk 16 is a lug 19 to 110

engage the depression 20. The opposite ends of the arcuate depression 20 have shoulders 21 and 21^a. When the lug 19 is in engagement with the shoulder 21^a, the openings 11 and 15 are in registration allowing the ink to enter the ink well from below. When the lug 19 is in engagement with the shoulder 21 of the arcuate depression 20 the openings 11 and 15 are out of registration, thereby 10 preventing the escape of the ink when the well is in its raised position.

It will be seen that with this construction the bottle may be at any time corked and the ink well lowered into the bottle and then 15 when it is desired to use the ink, assuming that the ink well is filled, the valve 10 may be rotated to close the drainage opening 15 and the ink well raised into the neck of the bottle, and engaged therewith by means of 20 the screw-threads 22. If it be desired to drain off the ink in the ink well 12 while it is in its raised position, the valve 10 may be rotated to that end to bring the apertures 11 and 15 in coincidence.

25 The invention having been fully set forth, what is claimed as new and useful is:—

1. In a combination ink bottle and ink well, the combination with the ink bottle having the interior of its neck threaded, of 30 a cork provided with a tubular extension engaging the neck, an ink well mounted on the lower end of the extension and having its bottom provided with an opening, a valve disk provided with an opening to coöperate 35 with the opening in the bottom of the ink well, and having a stem rotatably mounted in said extension, and means to manipulate the stem and the valve, said ink well having threads to engage the threads of the neck of 40 the bottle.

2. The combination with an ink bottle, of an ink well located therein, a cork to engage the neck of the bottle, connections between the cork and the well, whereby when the 45 cork is removed and raised, the ink well may be connected to the interior of the neck, detachable connections between the well and

the neck, and means to permit filling and emptying the ink well.

3. The combination with an ink bottle, of 50 an ink well located therein, a cork mounted in the neck of the bottle, a tubular guide connection between the stopper and the ink well, whereby when the stopper is removed the ink well may be raised to a position in 55 the neck of the bottle, detachable connections between the ink well and the neck of the bottle, and means to permit of the filling and emptying the ink well, and including a stem mounted in said tubular guide, and means 60 for manipulating the stem.

4. The combination with an ink bottle, of 65 an ink well located therein, a stopper engaging the neck of the bottle, guide connections between the stopper and the well whereby as the stopper is raised, the ink well may be positioned within the neck of the bottle, means including a stem mounted in the guide connections to permit of the filling and emptying of the ink well, means carried by 70 the upper end of the stem for rotating the same, and including means to limit the stem in different adjusted positions whereby said means may be opened or closed.

5. The combination with an ink bottle 75 having a mouth provided with threads, of an ink well, and a bottle stopper operatively connected to the ink well so that the ink well may be raised into the mouth of the ink bottle or depressed into the ink bottle, said 80 ink well having threads to detachably engage with the threads of the mouth of the bottle.

6. An ink bottle, a stopper therefor, an ink well, a support for the latter operatively attached to the stopper, the ink well being adapted to engage with the mouth of the bottle and form a stopper for the same when the real stopper is raised, and a valve controlling the flow of ink into and from the 90 ink well.

In testimony whereof I hereunto affix my signature.

JOHN M. SMITH.
